(57) **CLAIM**

The ornamental design of a rotating and self-supporting media player, as shown and described.

DESCRIPTION

A portion of this patent document contains material which is subject to copyright protection. The copyright owner has no objection to the facsimile reproduction by anyone of the patent document or the patent disclosure, as it appears in the Patent and Trademark Office patent files or records, but otherwise reserves all copyrights whatsoever.

FIG. 1 is a perspective view of a rotating and self-supporting media player showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view thereof, shown in rotated position; and,

FIG. 9 is a front view of FIG. 8.

The Broken line showings throughout the views are for illustrative purposes only and form no part of the claimed design. The broken lines, which define the bounds of the claimed design, form no part of the claimed design.
